DESIGN FOR A SPOON OR OTHER ARTICLE OF FLATWARE

John P. Petterson, Chicago, Ill.

Application May 5, 1938, Serial No. 77,010

Term of patent 14 years

To all whom it may concern:

Be it known that I, John P. Petterson, a citizen of the United States, residing at 55 East Washington Street, Chicago, in the county of Cook and State of Illinois, have invented a new, original, and ornamental Design for a Spoon or Other Article of Flatware, of which the following is a specification, reference being had to the accompanying drawing, forming part thereof.

In the drawing:—

I claim:

The ornamental design for a spoon or other article of flatware, as shown.

JOHN P. PETTERSON.
